UNITED STATES PATENT OFFICE.

LOUIS D. RESCH, OF CHICAGO, ILLINOIS.

NEWS-STAND.

1,295,209.

Specification of Letters Patent. Patented Feb. 25, 1919.

Application filed October 19, 1917. Serial No. 197,475.

To all whom it may concern:

Be it known that I, LOUIS D. RESCH, a citizen of the United States, residing at Chicago, in the county of Cook and State of Illinois, have invented certain new and useful Improvements in News-Stands, of which the following is a specification.

This invention relates to news stands, and more particularly to a news-stand of sheet metal construction provided with special closure means.

One of the main objects of the invention is to provide a news-stand of simple construction which may be produced at low cost, having a top and a cover coöperating therewith so constructed as to effectually prevent the entry of moisture into the interior of the same. A further object is to provide a cover which coöperates with the top of the casing or body portion of the news-stand so as to effect a moisture proof closure therewith when the cover is in lowered position. A still further object is to provide a retaining plate for articles placed on a shelf within the casing, this plate being so mounted as to provide means for securing the cover in closed position. Further objects will appear from the detail description.

In the drawings:

30 Figure 1 is a front view of a stand constructed in accordance with my invention

Fig. 2 is an end view

Fig. 3 is a section taken substantially on line 3—3 of Fig. 2

35 Fig. 4 is a section taken substantially on line 4—4 of Fig. 1

Fig. 5 is a fragmentary top plan view

Fig. 6 is a fragmentary transverse sectional view showing the cover in raised or 40 open position and the front retaining plate in raised position.

The casing designated generally by A is of substantially rectangular or box shape. This casing is provided, at each end, with 45 the semi-elliptical angle frame 1. An end plate 2 is secured to each of these frames and coöperates with the front plate 3 and back plate 4, which are also secured to the end frames, to form the body of the casing. One 50 of the end plates 2 is provided with a suitable opening which is normally closed by a door 5 hingedly secured at one end to one leg of one of the end frames, as at 6. This door is provided, at its other end with a hasp 55 7 which fits about a staple 8 secured to the

other leg of end frame 1, this staple being adapted to receive the bolt of a lock 9 for securing purposes. A shelf 10 is secured in casing A at the upper edge of front wall 3 and coöperates with the bottom 11 of the 60 casing to provide a storage space for the papers kept in stock.

Back plate 4 is extended and secured to the upper portion of each of the end frames 1 to provide a rounded top 12. The upper 65 edge portion of top 12 is turned upward and outward to provide a rearwardly directed bead 13 which is adapted to coöperate with an oppositely directed bead 14 provided at the rearward edge of the closure member or 70 cover 15. This cover is formed from sheet metal of suitable gage and is slidably mounted, at each end, in angular guide members 16 which are mounted in concentric spaced relation to the upper portions of end 75 frame 1. These members provide guide ways which extend above the top 12 of the casing. As will be noted more particularly from Figs. 1 and 4 of the drawing, members 16 are extended to provide vertical guide 80 members 16^a at the front of the casing, for the purpose which will be later disclosed.

A flat rectangular plate 17 is slidably mounted at each end in the guide members 16^a. The upward movement of this plate in 85 members 16^a is positively limited by the round or arcuate shape of the members 16. A hasp 18 is secured to cover 15 at the center thereof. This hasp is so bent as to fit about the tubular bead or roll 19 provided 90 at the front edge of cover 15. Hasp 18 co- operates with a staple secured in the plate to provide means for securing the cover to plate 17. As the upward movement of the plate is positively limited, the cover may be 95 thus effectually secured in closed position. When the cover is raised, plate 17 may be forced upward into the guide ways of members 16 so as to have its end portions slightly distorted. This causes the plate to jam or 100 bind in the guide members so as to be frictionally secured in raised position. In this position the upper edge portion of the plate projects above the shelf 10 so as to provide a retaining member for articles placed upon 105 the shelf.

When the cover is in lowered or closed position the beads 13 and 14 are in interlocking engagement and serve to provide a double moisture proof closure at the top of the 110

casing, the cover and top 12 forming a practically continuous rounded surface which will readily shed any moisture which may collect upon the same. In addition, the 5 beads serve to positively prevent the cover from being moved downward too far, thus effectually eliminating all danger of jamming or binding of the cover in the guide members.

10 A stand constructed in this manner may be readily produced at relatively small cost and serves to effectually protect the papers from the elements while providing means whereby the papers may be displayed to advantage and readily stored. If desired, one or more shelyes 20 may be mounted above shelf 10 in superposed relation on angle brackets 21 secured to the end plates 2. A display rack 22 is secured at each end of the 15 casing and is specially adapted for displaying magazines and similar articles. A strip 23 is secured to end plate 1 above the door 5. The lower edge portion of this strip is turned up to provide a trough 24 which extends above the edge of the door. This trough serves to prevent entry of moisture above the door.

As will be noted more particularly from Fig. 1 of the drawings, the movable cover section 15 is provided, adjacent each end, with a reinforcing strip 24. This strip serves to reinforce the cover section and prevent distortion thereof. The plate 17 is also provided, adjacent each end, with a reinforcing strip 25 secured thereto. These 20

strips serve to increase the rigidity of the plate and prevent distortion thereof.

What I claim is:

1. A stand for news papers having a casing provided with a rounded top, and a cover 40 slidably mounted above the top, the said top and cover being provided at their forward and rearward edges, respectively, with oppositely directed beads adapted to interengage so as to form a moisture tight closure 45 and to positively limit movement of the cover, when said cover is moved into closed position.

2. A stand for news papers having a casing the back wall of which is extended and 50 bent to form a rounded top, arcuate guide members mounted at the top of the casing above said top and concentric therewith, a cover slidable in said guide members, straight guide members mounted on the 55 front wall of the casing and forming continuations of said arcuate guide members, a flat plate mounted in said straight guide members for vertical movement in the same, said plate having its upward movement positively limited by the arcuate guide members, and means for securing the cover to the plate, the plate thus acting to secure the cover in closed position.

In testimony whereof I affix my signature 60 in presence of two witnesses.

LOUIS D. RESCH.
